PLASTIC SHEET MATERIAL

John R. Ellefson, Newburgh, N.Y., assignor to E. I. du Pont de Nemours and Company, Wilmington, Del., a corporation of Delaware

Application July 29, 1959, Serial No. 56,994

Term of patent 14 years

(Cl. D87—3)

The figure is a plan view of a plastic sheet material, showing my new design. A complete unit is enclosed within the broken lines and the design is repeated in regular order in all directions.

I claim:

The ornamental design for a plastic sheet material, substantially as shown and described.
